UNITED STATES PATENT OFFICE

FREDRIK LEONARD ERIKSSON, OF GEFLE, SWEDEN

PURSE

Application filed December 3, 1928, Serial No. 323,469, and in Sweden December 10, 1927.

Men usually carry their purses in a trousers-pocket and therefore, when a person is wearing an overcoat, it is quite a trouble to take out the purse, for instance in a street, 5 in a street-car, or the like. If the purse is placed loose in an outside pocket, one runs the risk of dropping the purse or having it stolen, and this, of course, is also the case with loose coins. In order without risk to 10 keep the purse easily accessible, for instance in an outer pocket, it must be secured in some suitable manner, but in such case the purses now in use must be capable of being unfastened for the purpose of taking out coins 15 which must either be picked up or, by folding up the purse, be poured out of the same, and in either case it is necessary to pull the purse out of the pocket. Furthermore, both hands will be occupied when opening and picking 20 coins from a purse according to any of the constructions hitherto known.

The present invention relates to a purse the bottom of which is adapted to be opened by a simple manipulation with the inside of 25 the hand held below the purse in order to let out coins into the hand. A purse arranged in this manner need thus not be pulled out of the pocket, and may therefore be secured in an outer pocket, or in any other easily 30 accessible place. The inlet opening of the purse is preferably made in the shape of a narrow slot that is adapted to be closed by spring action, so that the coins can easily be put into the purse, after which the opening 35 is automatically closed and prevents the coin from being taken out or discharged this way. There is thus no risk of the coins placed in the purse being stolen or shaken out.

In the accompanying drawings two 40 embodiments of the invention are illustrated. Figs. 1 and 2 show a purse according to one embodiment of the invention, viewed from the side and in section on the line II—II in Fig. 1, respectively. Figs. 3 to 5 show the bottom of the purse, viewed from the right in Fig. 1 in closed, semi-opened, and fully 45 opened position, respectively. Fig. 6 shows the upper portion of the purse in cross section. Fig. 7 shows the manner of opening 50 the purse. Figs. 8 and 9 show the bottom

portion of a purse according to a second embodiment, viewed from the side and from the right in Fig. 8 partly in section, respectively.

The purse 1 is made of soft leather or 55 strong cloth in a shape of a pocket which may be opened at the top as well as at the bottom. The top opening 2, which serves to introduce the coins in the purse, is provided at one side with a plate spring 3, and below 60 said spring a channel-shaped metal strip 4 is secured to each side of the purse 1, said two strips being normally held pressed against each other by means of the spring 3 which is secured by means of two spring links 65 32 to the outer strip 4, while the inner strip 4 is secured to the rear portion of the purse by means of two other spring links 33. Provided at the lower portion of the purse 1 are two metal edgings 7 and 8 hinged to each 70 other by means of hinge pins 5 and 6, and secured to each edging is a lever 9 and 10, respectively, which are moved away from each other by a spring 11 mounted on an extension of the hinge pin 6, so that the edgings 7 and 8 are held pressed against one 75 another.

Extending across each edging 7 and 8, respectively, is a strip 12 and 13, respectively, which strips are located opposite one another, a number of pins 14 being secured to the strip 12 and having their outer ends adapted to enter corresponding apertures in the strip 13. The distance between said pins is so dimensioned that only small coins can pass. 80 Secured to the front side of the purse 1 is a pocket 16 which is covered by a flap 17 provided with a lock 34, and is intended for banknotes, tickets, and the like. The purse is placed in an easily accessible place in the 85 clothes, for instance in a pocket 18 in the overcoat, and it may be secured, for instance buttoned, with its back to the inside of the pocket, preferably with its upper edge under a flap 19 sewn to the edge of the pocket.

For placing coins in the purse one pushes the fingers through the opening 2 which is widened against the action of the spring 3, so that the strips 4 are moved away from each other and give place to the coin. When the 100

6 fingers are withdrawn from the opening 2, the strips 4 are again moved together by the spring 3. For removing coins from the purse one puts the hand into the pocket below the bottom of the purse in the position shown in Fig. 7, and presses the levers 9 and 10 towards one another, whereby the edgings 7 and 8 are moved away from each other.

10 In the half-open position shown in Fig. 4 in which the opening between the edgings 7 and 8 is large enough for letting out coins, the pins 14 have not yet been moved so far aside that the large coins above the same can pass, and therefore only the small coins below the pins 14 are discharged. By pressing the levers 9 and 10 still further against each other the edgings 7 and 8 are moved to the position shown in Fig. 5, in which the pins 14 give free passage to the coins above the same, so that the purse will be completely emptied. Thus, if it is desired to remove small coins only from the purse, one moves the levers 9 and 10 slightly together to move the edgings 7 and 8 apart to half-open position, which adjustment one easily grows accustomed to. When it is desired to take out also large coins, the levers 9 and 10 are moved further together, so that the bottom of the purse is opened completely and all coins drop out.

15 In the embodiment described, the pins 14 are rigidly secured to the strip 12, so that a comparatively large opening movement of the edgings 7 and 8 is required in order that the ends of the pins 14 shall give free passage to the large coins. By making the pins 14 pivoted and allowing them to cooperate, for instance, with a cam disk or the like actuated when the levers 9 and 10 are pressed together, 20 said pins may be caused to drop in a certain opening position, again to be swung up by means of the cam disk when the levers 9 and 10 are released. In this case the edgings 7 and 8 may be given a less opening movement, but the device becomes more complicated.

25 In the embodiment illustrated in Figs. 8 and 9, pivotally mounted one above the other in a mounting 20 open at the bottom are a yoke 21 with a bottom 23, and a sleeve 22 open at the bottom and consisting of two portions pivoted to one another. Secured to the yoke 21 and to the outer portion of the sleeve 22 is a lever 24 and 25, respectively, each of which is adapted to be moved against the action of a spring 26 against an arm 27 and 28, respectively, secured to the mounting 20. The pins 14 serving to assort the coins, are secured to the mounting 20. As will be seen from Fig. 8, the upper edge of the front side of the mounting 20 is provided with approximately semi-circular recesses 29 between the pins 14, which recesses are engaged by corresponding flaps 30 at the lower edge of the front portion of the sleeve 22. The purpose of this arrangement is to render it possible for the large coins

70 to place themselves between the pins 14 and to be discharged without being hindered by the upper edge of the front side of the mounting 20, the points 31 of which projecting close to the pins 14 still prevent the coins from moving past the ends of the pins down into the space for the small coins. With this arrangement it is possible to take out small coins only 75 from the lower space, by moving the yoke 21 outwards, or large coins and such small coins as may remain in the upper space, by turning the outer portion of the sleeve 22 outwards, whereby, after a certain outward movement of said portion, the inner portion of the sleeve 22 is entrained by a stop 35 provided at the lower edge of the outer portion of the sleeve striking against a pin 36 provided at one side of the inner portion of the sleeve.

80 The inner portion of the sleeve 22 is then turned so far outwards that the coins move free from the pins 14. By cautiously opening it is possible to take out only some of the coins in the two spaces. By the outer portion of the sleeve 22 being pivotally connected to the inner portion of the sleeve the coins are prevented 85 from sticking in the sleeve. If the spring 26 actuating the lever 25 is not capable of counter-acting the outward pressure of the coins on the outer portion of the sleeve 22, so that said portion might swing out and discharge the coins above the pins 14, a suitable locking device may be provided for said outer portion which is released, for instance, 90 upon actuation of the lever 25.

95 It will be understood that the purse can also be used with advantage by ladies, and be secured, for instance, to the inside of the coat, in an ordinary handbag, or in a pocket, just as in a man's garment.

100 The purse above described and illustrated is, of course, only selected as an example of a suitable manner in which the invention may be carried out, and may therefore be modified in several ways without departing from the principle of the invention.

105 I claim:

110 1. A purse having an upper inlet opening adapted to allow the simultaneous introduction of a number of coins of different sizes, a normally closed bottom discharge opening adapted when open to effect the simultaneous discharge of several coins of different sizes contained in the purse above said discharge opening, said bottom discharge opening consisting of two hinged flaps, means for holding said flaps closed, and means for separating said flaps.

115 2. A purse having an upper inlet opening adapted to allow the simultaneous introduction of a number of coins of different sizes, a normally closed bottom discharge opening adapted when open to effect the simultaneous discharge of several coins of different sizes contained in the purse above said discharge opening, means dividing the inside of said

purse into an upper and a lower space, said means allowing small coins only to pass into said lower space, and means for opening said bottom discharge opening and simultaneously retracting said dividing means so as to permit communication between said upper and lower spaces.
